UNITED STATES PATENT OFFICE

THOMAS F. STUART AND HENRY A. MOORE, OF LOS ANGELES, CALIFORNIA; SAID STUART ASSIGNOR TO MARY E. BIGELOW AND SAID MOORE ASSIGNOR TO ALBERT H. BRUNNER, BOTH OF LOS ANGELES, CALIFORNIA

PUSH CATCH FOR DOORS

Application filed April 11, 1929. Serial No. 354,213.

Our invention relates to a push catch for doors, panels and the like, and has for its principal object, the provision of a relatively simple, practical and readily installed latch device that is released by the action of a push rod and which latch automatically moves into latching position under the influence of a spring.

The particular form of push catch herein disclosed is an improvement upon the push catches set forth in our copending applications for U. S. Letters Patent filed June 29th, 1927, Serial No. 202,387, and application Serial No. 243,144, filed December 28th, 1927.

Further objects of our invention are, to generally improve upon and simplify the construction of the push catches disclosed in our aforesaid copending patent applications, as well as other similar forms of latching devices, further to provide a latch that is readily adjustable so that it may be applied to doors and panels of different thicknesses and further, to provide a latch of the character referred to so that it may be utilized in connection with knobs of glass, metal or composition and which knobs are provided with threaded portions that are screwed into threaded recesses formed in the doors to which the push catches are applied.

With the foregoing and other objects in view, our invention consists in certain novel features of construction and arrangement of parts that will hereinafter be more fully described and claimed and illustrated in the accompanying drawings, in which:

Fig. 1 is a horizontal section taken through a portion of a door and showing our improved push catch applied thereto.

Fig. 2 is a top plan view of the housing of the catch and which housing contains the latching bolt and its actual mechanism.

Fig. 3 is a top plan view of the housing of the catch with the cover plate removed.

Fig. 4 is a longitudinal vertical section taken on the line 4—4 of Fig. 2.

Fig. 5 is a longitudinal vertical section taken on the line 5—5 of Fig. 3.

Fig. 6 is an enlarged cross section taken on the line 6—6 of Fig. 2.

Fig. 7 is a detail elevational view partly

in section and showing the head that is applied to the push rod.

Referring by numerals to the accompanying drawings which illustrate a practical embodiment of our invention, 10 designates a substantial rectangular housing, preferably pressed from sheet metal and having on its inner side a removable cover plate 11 that is held on the housing by means of lips 12 that are bent from the walls of said housing inwardly over the edges of said cover plate. Projecting from the side walls of the housing 10 are perforated ears 13 which receive screws 14 and the latter being seated in the door or panel 15 to which the latch is applied.

Secured to cover plate 11 is an outwardly projecting externally threaded tube 16, the same projecting through an aperture 17 that is formed in door 15 and screw seated on this threaded tube is the internally threaded reduced inner end portion 18 of a tube 19 that extends through an axial opening that is formed in a knob 20, preferably of glass, porcelain, metal or composition.

Projecting inwardly from the body of the knob 20 is an externally threaded lug 21 that is screw seated in a threaded recess 22, and the latter being formed in the outer portion of the door 15 in alignment with the opening 17.

Arranged to slide longitudinally within the housing 10 is a frame 23, from the forward end of which projects a latching member 24, the latter projecting through an opening in the corresponding end wall of housing 10, and which latching member is adapted to engage behind a striking plate 25 that is secured to the jamb 26, against which the door or panel closes.

The rearward sliding movement of frame 23, within the housing, is resisted by a spring 27, that is mounted on a support 28, and which latter engages the rear wall of the housing.

Pivots mounted on one of the side walls 95 of housing 10, near the forward end thereof, is one end of a link 29, the same extending rearwardly through the housing and its rear end being pivotally connected to a substantially triangular plate 30 that bears 100

against an upright portion of the sliding frame 23.

Arranged to slide vertically within the housing 10, directly above the link 29 is a plate 31 having projecting end portions 32 that enter vertically disposed grooves or guideways 33 and which latter are formed in the inner faces of the side walls of the housing.

10 Projecting from the rear edge of plate 31, adjacent to one end thereof, is a depending lip 34 that bears on top of link 29 near the point where the latter is pivotally connected to plate 30.

15 Rigidly fixed to the center of plate 31 and projecting downwardly through the housing 10 and through an opening 35, that is formed in the bottom wall of said housing, is a tubular member 36 that is in direct alignment 20 with tube 16 and the lower portion of this tubular member 36 is internally threaded as designated by 37 in order to receive the externally threaded end portion 38 of a push rod 39, and which latter extends through the 25 tube 16 and through the tubular member 19.

The outer end portion of push rod 39, or that portion that projects from the end of the tube 19 and the outer end of knob 20, is slightly increased in diameter, as designated 30 by 40 and mounted on said portion of increased diameter is a tubular shell 41 that carries at its outer end a small head or button 42. The inner end of the tubular shell 41 is pressed inwardly and clamped around 35 the shoulder between the enlarged portion 40 and the body of the push rod 39 (see Fig. 7).

The construction just described permits the head or button 42 to be readily secured on the outer end of the push rod.

40 Formed in one of the side walls of housing 10 and in transverse alignment with the tubular member 36 is a vertically disposed slot 43, through which projects a screw 44, and the inner end thereof passes through the wall of 45 the tube 36 and bears against the push rod 39, thereby locking said push rod to the tube 36 after said push rod has been adjusted by screwing same into and out of said tubular member 36.

50 Under normal conditions, or when the door to which our improved latch is applied is closed spring 27 forces frame 23 to its forward limit of movement in housing 10, so that the latching member 24 is positioned 55 behind the striking plate 25, thereby retaining the door in closed position, as illustrated in Fig. 1.

To release the latch and open the door the first and second fingers of the hand are positioned on opposite sides of the door knob 20 and by pressure of the thumb upon button 42, push rod 39 is moved inwardly a short distance, with the result that lip 34 or plate 31 will bear upon link 29 near the point where the same is pivotally connected to plate 30,

so that said link will be moved inwardly, thereby imparting corresponding movement to plate 30 so that the latter will act as a lever to move frame 23 rearwardly toward the housing against the resistance offered by spring 27, and when latching member 24 70 clears the striking plate the door may be opened.

Upon the removal of the thumb pressure from the outer end of the push rod spring 27 will act to restore the various parts of the latching device to their normal position, and when the door is subsequently closed the beveled edge of latching member 24 will engage 75 striking plate 25 and will move into the latch housing until it clears the striking plate and the compressed spring 27 will now act to force the frame 23 and latching member outwardly so that said latching member is positioned behind the striking plate and the door 80 will be latched in closed position.

Inasmuch as the reduced inner end portion of tube 19 is threaded upon tube 16, said tube 19 may be adjusted toward or away from the housing 10 and as a result the latch may 85 be readily and conveniently combined with doors of different thicknesses and with knobs of different lengths.

The inner end of push rod 39 has threaded engagement with the tubular member 36, thereby enabling the push rod to be readily 90 adjusted relative to said tubular member 36, and the frame actuating plate 31 that is carried by said tube and the screw 44 provides simple and efficient means for locking the 95 push rod to the tube 36 in differently adjusted positions.

Thus it will be seen that we have provided a push catch that is relatively simple in construction, capable of being easily and quickly 100 applied to a door or swinging panel, capable of being easily and quickly adjusted so as to be applied to doors and panels of varying thicknesses and the application of the catch to a door requires the formation of only a 105 single aperture in said door.

It will be understood that minor changes in the size, form and construction of the various parts of our improved push catch for doors may be made and substituted for those 110 herein shown and described without departing from the spirit of our invention, the scope of which is set forth in the appended 115 claims.

We claim as our invention:

1. In a push catch for doors, a housing adapted to be positioned on a door, a spring 120 pressed latch bolt arranged for sliding movement within said housing, a pair of toggle links arranged within said housing, one of which links is pivoted to the housing, the other link bearing on a part of the latch bolt, a plate arranged for sliding movement within the housing and bearing on one of the toggle links, the side walls of the housing 125 130

adjacent to the ends of said plate being provided with vertically disposed recessed guideways, extensions on the ends of said sliding plate, which extensions project into said guideways, a tubular member carried by said plate and projecting through an opening in one of the walls of the housing and a push rod having its inner end adjustably seated in said tubular member.

10 2. In a push catch for doors, a housing adapted to be positioned on a door, a spring pressed latch bolt arranged for sliding movement within said housing, a pair of toggle links arranged within said housing, one of which links is pivoted to the housing, the other link bearing on a part of the latch bolt, a plate arranged for sliding movement within the housing and bearing on one of the toggle links, a tubular member carried by said plate, a push rod having its inner end adjustably seated in said tubular member and means for locking said push rod to said tubular member in differently adjusted positions the outer portion of which locking means 25 passes through a slot in one of the walls in the housing.

3. The combination with a door provided in one side with a threaded recess and a latch housing located on the opposite side of the door, which latch housing contains a latching bolt and bolt retracting means, of a knob provided on one end with an integral thread that is adapted to be screw-seated in the threaded recess in the door, said knob having an axial bore, a tube seated in the bore in said knob, a threaded tube projecting from said latch housing, the outer end of which threaded tube is screw-seated in the inner end of the tube in said knob, and a longitudinally adjustable rod passing through said tubes for actuating said latch bolt retracting means.

In testimony whereof we affix our signatures.

45 THOMAS F. STUART.
HENRY A. MOORE.
